UNITED STATES PATENT OFFICE.

EDWARD JACOB ELSAS, OF KANSAS CITY, MISSOURI.

HYDROAEROPLANE.

1,127,211.

Specification of Letters Patent.

Patented Feb. 2, 1915.

Application filed January 13, 1913. Serial No. 741,860.

To all whom it may concern:

Be it known that I, EDWARD J. ELSAS, a citizen of the United States, residing at Kansas City, in the county of Jackson and 5 State of Missouri, have invented a new and useful Hydroaeroplane, of which the following is a specification.

This invention relates to hydro-aeroplanes, its primary object being to provide a machine of the monoplane type so constructed 10 as to travel with equal facility upon land and water and in the air, the steering means utilized being employed in guiding the machine under all conditions.

15 Another object is to provide improved means whereby the whole sustaining plane can be tilted about a transverse axis relative to the rudder frame so as thus to restore and maintain the longitudinal balance 20 of the machine, thereby preventing or materially reducing the forward or rearward dipping which, heretofore, has so often resulted disastrously to the occupants of machines in flight.

25 Another object is to provide means under the control of a single element designed to be grasped by the aviator, and whereby the various means employed for controlling the flight of the machine, are constantly 30 under the control of the aviator.

Another object is to provide a machine of this character the sustaining plane of which constitutes means for cooling the water used in connection with the motor, it 35 thus being possible to dispense with the resistance to flight heretofore offered by the radiators commonly in use.

Another object is to provide sustaining surfaces having corrugations extending in 40 the direction of the line of flight whereby the sustaining action of the air or water supporting the machine will be rendered more efficient and the danger of lateral dipping is reduced.

45 Another object is to provide combined keels and runners upon the bottom of the car or body, these runners being designed for use while traveling over ice surfaces the 50 runners being provided with means for preventing skidding upon the ice.

Another object is to provide a novel form of horizontal rudder.

Another object is to provide means whereby the plane sections can be rotated about their transverse axis so as to assume practically vertical positions whereupon they can be swung back quickly and easily into substantially parallel planes. 55

A further object is to provide improved means for supporting the machine while 60 traveling over the ground, the supporting wheels employed for this purpose being so mounted as to be readily shifted to or out of active positions.

With the foregoing and other objects in view which will appear as the description proceeds, the invention resides in the combination and arrangement of parts and in the details of construction hereinafter described and claimed, it being understood that 70 changes in the precise embodiment of the invention herein disclosed, can be made within the scope of what is claimed, without departing from the spirit of the invention.

In the accompanying drawings the preferred form of my invention has been shown.

In said drawings:—Figure 1 is a view partly in side elevation and partly in section of a machine embodying the present improvements, the position of the sustaining plane when swung about its transverse axis prior to being folded rearwardly, being indicated by dotted lines. Fig. 2 is a plan view of the machine, parts being broken away and the sustaining plane being shown 80 by dotted lines, swung backwardly to folded position. Fig. 3 is a front elevation of the machine, parts being broken away. Fig. 4 is an enlarged transverse section through the central section of the sustaining plane. Fig. 5 is a view partly in front elevation and partly in section of the steering post and adjacent parts. Fig. 6 is a front elevation of the meeting portions of the pivot rods on which the movable sections of the sustaining plane are mounted, said rods being shown locked together in their normal positions and the bearings of the rods being also shown. Fig. 7 is a section on line A—B Fig. 8 is an enlarged vertical trans- 95 100

verse section through one of the combined 5 keels and runners of the car or body and showing the shoe provided for engaging an ice surface. Fig. 9 is a view showing, diagrammatically, the steering post and various controlling cables adapted to be operated by the post and by the wheel supported thereby. Fig. 10 is a detail view of the clutch mechanism employed in connection with the front axle of the machine. Fig. 11 is a perspective view on an enlarged scale of certain of the controlling cables of the machine. Fig. 12 is a perspective view of the central or fixed sustaining plane and of adjacent parts, the support at the near side of the plane being shown in section. Fig. 13 is a perspective view of portions of the pivot rods on which the sustaining planes are adapted to be mounted, the said rods being separated and the coupling members being shown. Fig. 14 is a perspective view of one end portion of one of the coupling members and showing that side thereof not disclosed in Fig. 13. Fig. 15 is a section on line C—D Fig. 13. Figs. 16, 17, 18 and 19 are views showing diagrammatically, the action of the air upon the planes when the parts of the machine are adjusted to different positions relative to each other. Referring to the figures by characters of reference 1 designates a substantially canoe-shaped body or car, the same being provided with a bottom which is substantially straight from side to side and in which are formed longitudinal corrugations, indicated at 2 in Fig. 3. Arranged along the sides of the bottom of the car or body are runners 3, these runners being parallel and each being curved upwardly at its front end. As shown in Fig. 1, each runner may be provided with openings 4 whereby the weight thereof is reduced without sacrificing strength. The upwardly curved portions of the runners are provided with elongated shoes 5 formed preferably of steel, each shoe, as shown in Fig. 8, being formed with a channel 6 in its lower face whereby parallel cutting edges are produced as shown at 9. These edges are designed to cut into ice when the machine is traveling thereon and, therefore, prevent skidding. The runners 3 constitute keels when the machine is floating upon a body of water. A frame, indicated generally at 10, extends upwardly from and is fixedly connected to the car or body 1 and hingedly secured to the upper portion of this frame are rearwardly extending downwardly curved arms 11 which converge beyond the rear end of the body 1 and merge into a tubular spar 12 of any suitable length. Extending upwardly through the rear end portion of this spar 12 is a revoluble stem 13, the lower end of which is preferably forked, as at 14, so as

to receive a rear supporting wheel 15. This wheel is hollow and acts as a rotating support or pontoon when the machine is traveling on water. A vertical rudder 16 is connected to the upper portion of stem 13 and a spring 17 is interposed between the spar 12 and the fork 14 so as to constitute a cushion for the spar when the wheel 15 comes into contact with the ground. A wheel 18 is secured to the stem 13 between the spar 12 and the vertical rudder 16 and has forwardly extending cords 19 or the like secured thereto and extending partly therearound, these cords being carried forwardly along the spar 12. The cords are preferably crossed, as shown at 20 in Fig. 9 and extend past opposed portions of a guide sheave 21 and thence over and downwardly from guide sheaves 22 from which they enter the spar 12 and, after passing under guide sheaves 23, extend forwardly within the spar and partly around guide sheaves 24 to the front end portions of the arms 11 where guide sheaves 25 are located.

A hanger 26 extends downwardly from the spar 12 and has oppositely extending arms 27 connected, by rearwardly converging rods 28 hinged to the stem 13 at a point close to the fork 14. The arms 27 and rods 28 constitute braces for the stem 13.

Fixedly connected to the rear end portion of the spar 12 and extending laterally beyond both sides thereof is a stationary horizontal rudder 29 made up of a lower thickness 30 of rigid material and an upper thickness 31 of flexible material such as a light spring metal. This upper thickness extends rearwardly beyond the rear edge of the lower thickness 30 to form a thin flexible spring-like extension, and has its rear edge portion reinforced by a transverse rod 32 to the end portions of which are secured controlling cords 33. These cords extend downwardly and forwardly so as to pass under sheaves 34 mounted upon the axle of the wheel 15. From the sheaves the cords converge upwardly and forwardly and merge into a single actuating cord 35 which extends over a guide sheave 36 in the bottom portion of the spar 12 and thence extends longitudinally within the spar and along one of the arms 11 thereof to a sheave 37 disposed at the forward end of one of said arms. Suitable guide sheaves 38 may of course be arranged along the arms 11 and spar 12 so as to hold the cord in proper position relative to the spar and arm.

It is to be understood that the flexible member 31 of the horizontal rudder is normally under tension so that, when the cords 35 and 33 are paid out, this member 31 will swing upwardly from the position indicated by full lines in Fig. 1, to the position indicated by line 31^a, thus presenting its upper

surface to the air in the path of the rudder and operating to force the back end portion of the spar downwardly.

Fixedly mounted upon the frame 10 is 5 the middle section of the sustaining plane of the machine. This middle section, which has been indicated generally at 39, is made up of a slightly concaved lower thickness 40 and a curved upper thickness 41, the two 10 thicknesses being secured together along their front and back edges and the space between them being closed between the side edges of said thicknesses so as thus to form a closed compartment 42 through which circulates the cooling medium flowing through 15 the jacket of the motor 43. The section 42 is inclined downwardly and rearwardly or, in other words, converges rearwardly toward the body 1 and the bottom surface or 20 thickness 40 of this section 39 is corrugated longitudinally as shown at 44 in Fig. 4. Thus it will be seen that the heated water delivered from the jacket of the motor 43 will flow through a pipe 43' into the compartment 42 and be cooled by the air flowing 25 along the lower corrugated surface of the stationary plain portion 39. By corrugating the thickness 40, an increased area is presented to the liquid contents of the 30 section and it will be apparent that water will thus be cooled efficiently as though a radiator of a standard form was employed. The present cooling means is advantageous, however, because it offers practically no objectionable resistance while the machine is 35 in flight, whereas the radiators heretofore employed have afforded considerable resistance to the movements of the machines.

Arranged adjacent the sides of the upper 40 portion of frame 10 are rings 45 or the like having upwardly and downwardly extending trunnions 46 journaled in the frame.

Rings 45' are mounted in the rings 45 and have forwardly and rearwardly extending 45 trunnions 46' journaled in the rings 45.

Pivot rods 47 are journaled within the respective rings 45' and extend normally in opposite directions from the frame 10. These rods are adapted to be rotated within 50 the rings 45' and slidably mounted upon the inner end portion of one of the rods is a coupling sleeve 48 provided with a longitudinal slot 49 into which extends a guide pin 50 extending from said rod 47. One 55 end of the sleeve 48 has its rear half cut away, as shown at 51 and adapted normally to extend partly around the opposed rod 47. Secured on this last named rod 47 is a short sleeve 52 having a semi-cylindrical spacing 60 element 53 interposed between it and the rod 47 on which it is mounted, thus forming a semi-cylindrical recess 49', it being understood that the sleeve 52 and the spacing plate 53 are secured to the rods 47 in any suitable manner, as by means of a key 65 or the like. Thus it will be seen that when the sleeve 48 is shifted longitudinally, the semi-cylindrical projecting portion will enter the space 49' and not only result in holding the two rods 47 in alinement, but 70 also in preventing independent rotation of said rods.

An arm 54 is fixedly connected to the sleeve 48 and by means thereof the sleeve can be shifted in the direction of its length 75 along one of the rods 47, and into or out of engagement with the other rod 47. Furthermore, while the sleeve is in engagement with both rods, the arm 54 can be employed for rotating the two rods about their longitudinal axis. A bracket 55 is secured to the frame 10 and is adapted to be engaged by the free end portion of arm 54 so as thus to limit said arm in its movement in one direction. 85

A cable 56 is secured to the free end portion of the arm and extends rearwardly therefrom to a block 57 carrying a sheave 58.

Fixedly connected to each rod 47 is a movable section of the sustaining plane, each of 90 these sections, which have been indicated at 59, being made up of ribs 60 extending transversely of the rod and interposed between an upper curved thickness 61 and a lower thickness 62 which is curved to a 95 lesser degree. The two thicknesses meet along their front edges and the lower thickness extends rearwardly beyond the upper thickness, as shown particularly in Fig. 2.

That portion of the thickness 62 located 100 under the outer end ribs of the section 59 and back of the thickness 61 is divided from the remainder of the rearwardly projecting portion 62 by a slit or incision 63, whereby an aerofoil 64 is produced. The rear portions of the ribs 60 in this aerofoil are like those in all of the planes of the machine (thin and of spring material) and they are normally flexed downwardly. A reinforcing strip 65 is secured transversely of the aerofoil close to the back edge thereof and is pivotally and slidably engaged by one arm of a bell crank lever 66, as shown in Fig. 9, said lever being fulcrumed upon one of the ribs 60 and having its upwardly extending 110 arm secured to one end of a controlling cord 67. This cord extends forwardly between the thicknesses of the section 59 and partly around guide sheaves 68 and along the rod 47 to guide sheaves 69 mounted upon 115 the frame 10. From these sheaves the said cords extend to opposite sides of a tubular controlling post 70. A plate 71 is soldered or otherwise fastened to the bottom of the body or carriage 1 so as to bridge the upper 120 concaved surface of one of the corrugations and a stud 72 extends upwardly from the center of this plate and constitutes the een-

ter bearing of a substantially horizontal sheave 73. This sheave is adapted to rotate relative to the plate 71 and the lower end of the post 70 bears downwardly on the 5 sheave.

A spiral spring 74 extends around the lower end portion of the post and is secured at one end to the upper face of the sheave 73 while its other end is secured to the post 10 70. Mounted within the post is another spiral spring 75 which bears downwardly upon the closed lower end 76 of the post.

A flexible member 77 such as a metal cord, or the like, is attached to the upper end of 15 the spring 75 and to a bow spring 78 which bears upwardly against the plate 71 and is interposed between said plate and the bottom of the car or body. Thus it will be seen that the spring 75, which is constantly under 20 stress, serves normally to hold the post 70 perpendicular to the plate 71. At the same time the spring 74 which constitutes the sole connection between the post 70 and the sheave 73 will flex and thus permit swinging 25 movement of the post relative to the sheave while, at the same time, causing rotary motion to be transmitted from the post to the sheave.

The cords 19 hereinbefore referred to 30 extend partly around and are secured to the sheave 73 so that, when the sheave is rotated in one direction, the vertical rudder will be turned to the right while, when the sheave is rotated in the opposite direction, 35 said vertical rudder will be swung to the left. As the rear wheel 15 moves with the vertical rudder, it is apparent that the same means may be employed for guiding the machine while traveling over the ground, or 40 upon the water, the wheel 15, in connection with the rudder 16, serving to steer the machine while traveling on the water. As the post 70 is free to swing laterally by reason of the particular connection described, it 45 will be seen that when it is swung toward one side, the cords 67 will be actuated so as to elevate one of the aerofoils 64 whereas, when it is swung laterally in the opposite direction, the other aerofoil will be shifted. 50 These aerofoils it is to be understood are formed of spring metal and normally extend downwardly with the spring ribs 60 thereabove.

A hand wheel 79 is mounted for rotation 55 within the upper portion of the post 70 and has a sheave 80 revoluble therewith. Cords 81 are secured to and extend downwardly from said sheave and through the post 70, these cords extending outwardly from the 60 lower end portion of the post. One of the cords 81 extends rearwardly under a sheave 82 secured to the body or car 1 near the rear end thereof and thence upwardly to a cross bar 84 which is secured to and extends trans- 65 versely of the arms 11 and is fixedly connect-

ed to the arms. The other cord 81 extends forwardly from the post and under a guide sheave 85 secured in the body or car 1 adjacent its front end and thence upwardly over a guide sheave 86 secured to the front 70 end portion of the central or fixed section 39 of the sustaining plane. From this sheave the cord 81 extends rearwardly over a guide sheave 87 secured to the rear edge portion of the section 39 and thence downwardly to the cross rod 84 to which said cord 81 is fastened. Thus it will be seen that the two cords 81 constitute practically an endless cord extending from the wheel 80 to the cross bar or rod 84. 75

As the body or car is adapted to swing upon its hinge connection to members 11 as an axis, it will be apparent that such swinging movement will not be retarded by the cords 81 owing to the fact that the sheaves 85 and 82 which are secured to the body 1, 80 will travel along the cords during this swinging movement. When the spar 12 swings upward relative to the carriage 1, the distance between the sheave 82 and the cross 90 bar 84 will of course increase and when the spar 12 swings in the opposite direction this distance will diminish. 95

Secured to the block 57 of sheave 58 are 100 cords 90 which extend rearwardly between superposed sheaves 83 carried by the car and these cords 90 are attached to the cord 81. These cords 90 are normally slack, as shown so as not to interfere with the swinging movement of the spar 12 relative to the carriage 1. 105

A strong spring, indicated at 92, extends forwardly from the arm 54 and is secured to the central section 39 of the sustaining plane, this spring serving to pull normally 110 in a forward direction upon the arm 54 thus to hold the tiltable planes 59 normally in a predetermined relation to the fixed central plane 39.

It is to be understood that while the machine is in flight the same may be guided downwardly or upwardly simply by rotating the wheel 80 and thus causing one of the cords 81 to be wound upon the wheel while the other cord is paid out. As the two cords are connected to the arms 11 of spar 12, it will thus be seen that the said spar will be swung upwardly or downwardly relative to the suspended carriage 1. When the spar 12 is pulled downwardly, the angle of incidence of the sustaining planes 39 and 59 is diminished and the machine, while in flight, will be caused to travel in a substantially horizontal plane, as shown in Fig. 19. However, by pulling the spar 12 120 downwardly to a further extent, so as thus to draw the lower cord 90 against the pulley 83 and to cause said cord to pull upon the block 57, lever 54 will be drawn rearwardly 125 against the action of its spring 92, thus re- 130

ducing the angle of incidence of the sustaining planes 59 by causing the rods 47 to rotate and to swing the front ends of said sustaining planes 59 downwardly. Consequently the machine will thus be caused to dip downwardly and forwardly, this operation being particularly desirable in effecting a quick landing. In this connection see Fig. 16 wherein the relative positions of the sustaining planes 39 and 59 have been indicated by full and dotted lines respectively, when the lower cord 90 is drawn taut by the excessive lowering of the spar 12. In this figure, furthermore, the direction of flight under these conditions is indicated by the arrow *f*. When the spar 12 is swung upwardly to any extent without drawing the upper cord 90 taut, the upward flight or ascent of the machine can be effected. This is due to the fact that the upward movement of the spar brings the upper surface of the tail plane or horizontal rudder into action, so that the air pressure against said rudder 31 will tend to push downward the rear end of the spar 12 and, consequently, tilt upwardly the sustaining plane 39 which is fixedly connected to the car or carriage. The sustaining planes 59 will also, under normal conditions, tilt with the plane 39, the planes 59 being held against independent movement by the spring 92. Fig. 17 illustrates the action of the machine under the conditions just described the direction of flight being indicated by the arrow *f* while the air pressures are indicated by the remaining arrows. If, however, the spar 12 should be swung upwardly to an excessive extent, thus to draw the upper cord 90 taut against the upper pulley 83, said cord will pull on the lever 54 and thus swing the forward edges of the sustaining planes 59 downwardly, thereby reducing the angle of incidence thereof and tending to restore the machine to its substantially horizontal flight, as will be apparent by referring to Fig. 18, wherein it will be seen that the tilted sustaining planes 59 will displace air upwardly, thus tending to offset the downward displacement of air by the plane 39 and by the rudder 31.

The cord 35 extends rearwardly from the sheave 37 and over a guide sheave 93 supported by the rear portion of the central sustaining section 39 of the plane and thence downwardly under the upper guide sheave 83. From this sheave the cord 35 extends forwardly into engagement with sheave 58, thence rearwardly around the lower sheave 83 and back to sheave 58 from which it extends over the lower sheave 83 and thence downwardly under sheave 94 and forwardly to the post 70. A slack cord 97 connects this cord 35 to the block 57, said cord being extended between the sheaves 83. The said cord is attached to the post as shown so

that, when the post is swung forwardly, it will pull on the cord 35 and cause the rear end portion of the horizontal rudder 31 to be flexed downwardly.

The cords 19 extend rearwardly from their guide sheaves 25 and over guide sheaves 95 from which they extend downwardly under guide sheaves 96 secured within the body or carriage 1, these cords being then extended forwardly to the wheel 73 so that, when said wheel is rotated by revolving the post 70, motion is transmitted therefrom through the cords 19 to the vertical rudder and to the rear supporting wheel.

As has already been pointed out, the operation of the aerofoils can be controlled by swinging the post 70 laterally so that motion will thus be transmitted from the post through the cords 67 to the aerofoils.

In order that the machine may travel freely over the ground, front supporting wheels 98 are provided in addition to the wheel 15, these supporting wheels being journaled upon crank arms 99 located at the ends of an axle 100 extending transversely of the front portion of the body 1. This axle is adapted to be rotated by means of a lever 101 so located as to be conveniently grasped by the aviator, said lever controlling means whereby the wheels 98 can be readily shifted into or out of active positions. The mechanism for controlling the movement of the front supporting wheels into and out of active positions, includes a coiled spring 102 fixedly connected in any suitable manner at one end to the axle 100 and having its other end secured to a clutch member 103 provided with ratchet teeth. These ratchet teeth normally engage similar teeth formed upon a clutch member 104 which constitutes the lower end of the lever 101. Lever 101 is normally held against movement by any one of a series of teeth 105 arranged upon the gunwale of the body 1. With the lever thus locked, as shown by full lines in Fig. 1, it will be apparent that the crank arms 99 will be extended downwardly and rearwardly, as shown by full lines in Fig. 1 and a limited upward and rearward movement of the wheels 98 is permitted inasmuch as the spring, being secured at its respective ends to the axle 100 and to the clutch member 103, operates as a cushion.

During this swinging action, the clutch member 103 presses against the teeth of the clutch member 104 and is thus held against movement as long as lever 101 is locked. When it is not desired to use the supporting wheels, lever 101 is swung backwardly, thus carrying the wheels forwardly until, aided by the upward pressure of the support upon them, the axle is rotated so as to bring catch 106, which is on lever 101, into engagement with a notch 105 formed within clutch mem-

ber 103. This operation occurs just as the wheels clear the ground and locks them in such position for use as safety bearings while the machine is traveling upon the 5 runners. Also it is to be understood that by unlocking the latch the wheels may be brought entirely up by hand as shown by dotted lines in Fig. 1.

The motor 43 drives a propeller 107 which 10 is supported in front of the section 39 of the sustaining plane.

While the machine is traveling over a solid surface, it is desirable that the machine be arranged to readily pass obstructions, 15 through gates, along lanes, and in through doors of hangars and, with this idea in mind, the sustaining planes have been so mounted as to be foldable back against the side portions of the machine. This folding 20 is effected by first swinging arm 54 rearwardly so as to tilt the movable sections of the sustaining plane downwardly to the positions indicated by dotted lines at 108 after which said lever 54 is shifted laterally, 25 thereby moving the coupling sleeve 48 out of engagement with the slotted portion 53 of one of the rods 47. The two tilted sections of the plane are then swung rearwardly to the positions indicated by dotted 30 lines at 109 in Fig. 2, this rearward swinging movement being possible in view of the fact that the rods 47 are mounted in rings 45 having vertical trunnions 46. The resistance offered by the atmosphere against 35 the tilted sections will be sufficient to cause them to swing backwardly to the positions indicated by dotted lines in Fig. 2. By pulling backwardly on lever 54 the sustaining planes can be swung forward together 40 so as assume positions for joining the rods 47 by means of sleeve 48. This movement of the planes in unison can be effected by means of a crossed belt 48^a mounted on sheaves 48^b secured to the trunnions 46.

45 As shown in Fig. 3 deflecting wings 110 may be provided at the sides of the front portion of the body 1 so as thus to deflect outwardly any water which may work up upon the sides of the body while the machine is floating.

The central section of the sustaining plane is preferably thinner than the remaining or side sections, the space therein, however, affording ample accommodation for the 55 water being cooled. By making this central section thin, the motor need not be elevated as far as would be necessary otherwise.

What is claimed is:—

1. A machine of the class described, including a body, a sustaining plane thereabove and including a central section fixedly mounted relative to the body and side sections tiltably mounted relative to said body, a coupling constituting a connection 60 between the movable sections of the plane,

means for tilting the movable side sections of the sustaining plane simultaneously about an axis extending transversely of the line of flight, said coupling being shiftable to disconnect the tilttable side sections of 70 the sustaining plane, and hinge connections between said side sections and adjacent portions of the machine, said side sections being adapted to swing rearwardly and inwardly when tilted out of sustaining position. 75

2. A machine of the class described including a sustaining plane made up of a central fixed section and side movable sections cross rods on which the side sections 80 are mounted, means for coupling the rods together for rotation in unison, means for rotating the rods to tilt the forward ends of the movable plane sections downwardly, said coupling being shiftable by said last 85 named means to disconnect the rods, said rods being adapted to swing rearwardly while the sections are in tilted positions.

3. A machine of the class described including a sustaining plane made up of a central fixed section and side movable sections, cross rods on which the side sections are mounted, means for coupling the rods together for rotation in unison, means for rotating the rods to tilt the forward ends 95 of the movable plane sections downwardly, said coupling being shiftable by said last named means to disconnect the rods, said rods being adapted to swing rearwardly while the sections are in tilted positions, 100 and each of said movable sections including an aerofoil adjacent its outer side, and means supported below the fixed section for actuating the aerofoils.

4. A machine of the class described including a sustaining plane made up of a central fixed section and side sections, said side sections being tilttable about an axis extending transversely of the fixed central section, a body suspended below and fixedly connected to the central section, each of said movable sections having a non-flexible front portion, and an integral rear flexible portion at its outer end constituting 110 an aerofoil, and means operable from a 115 point within the body for shifting either of the aerofoils relative to its plane section.

5. A machine of the class described including a sustaining plane made up of a central fixed section and side movable sections, a body suspended below and fixedly connected to the central section, each of said movable sections having a non-flexible front portion, and an integral rear flexible 125 portion at its outer end constituting an aerofoil, means operable from a point within the body for shifting either of the aerofoils relative to its movable side section, and means for tilting the movable side sections 130

simultaneously about an axis extending transversely of the line of flight.

6. A machine of the class described, including a sustaining plane made up of a central section and side sections, a body suspended below and fixedly connected to the central section, said side sections being tiltable about an axis extending transversely of the central section, a tail piece extending rearwardly from and adapted to swing upwardly and downwardly about said axis of the side sections, means under the control of the aviator for swinging the tail piece upwardly and downwardly relative to the body and the central section, and means operated by the movement of the tail piece relative to the body and central section for producing relative movement of the side and central sections about said axis of the side sections.
10. 7. In a machine of the class described, the combination with a sustaining plane including a central fixed section and side movable sections, of a body suspended below and fixedly connected to the central section, an arm suspended below and adapted to swing relative to the central section and constituting means for tilting the movable sections in unison about an axis extending transversely of the fixed section, a tail piece including a structure extending rearwardly from said axis and rudders carried by the structure, means for shifting the said tail piece upwardly and downwardly about said axis and relative to the body and central section, and means operated by the excessive swinging movement of the tail piece relative to the central plane section, for actuating the arm to change the relative positions of the movable and fixed plane sections.
15. 8. A machine of the class described including a sustaining plane made up of a central section and side sections, said side sections being movable about an axis extending transversely of the line of flight, aerofoils carried by said side sections at the outer ends thereof and adapted to flex along lines extending transversely of the line of flight, a structure extending rearwardly from and hingedly connected to the central section of the sustaining plane, a vertical rudder mounted on said structure, a horizontal rudder, said horizontal rudder having a rigid front portion and a flexible rear portion, a body supported below and fixedly connected to the central section, an endless connection between said body and the rearwardly extending structure, a post mounted to swing within the body and to rotate about an upwardly extending axis, means actuated by the rotation of the post for operating the vertical rudder, means operated by the swinging of the post forwardly and rearwardly, for actuating the flexible portion of the horizontal rudder, means actuated by the lateral swinging movement of

the post for actuating the aerofoils, a hand wheel carried by the post and movable relative thereto to operate said endless connection and shift the rearwardly extending structure relative to the body.

9. In a machine of the class described the combination with a sustaining plane including a central section and side sections, said side sections being adapted to move together about an axis extending transversely of the line of flight, of a structure extending rearwardly from and hingedly connected to the central section, a horizontal rudder carried thereby and including a front rigid portion and a rear flexible portion, a body below and fixedly connected to the central section, an endless flexible element secured to the rearwardly extending structure and movably engaging the central section of the sustaining plane and the body, an arm movable with the movable sections and extending downwardly toward the body, manually operated means carried by the body for actuating said flexible element to shift the rearwardly extending structure toward or from the body, means operated by the said structure when swung to and beyond a predetermined position relative to the body for actuating the arm to tilt the movable plane sections, and means actuated by said relative movement of the structure for actuating the flexible portion of the horizontal rudder.

10. In a machine of the class described, the combination with a sustaining plane including a central section and side sections, said side sections being movable together about an axis extending transversely of the line of flight, of a rearwardly extending structure hingedly connected to said central section, a horizontal rudder carried by the structure and including a front rigid portion and a rear flexible portion, a body below and fixedly connected to the central section of the sustaining plane, and means operated by excessive movement of said structure relative to the body for tilting the movable plane sections and flexing the horizontal rudder, simultaneously.

11. In a hydro-aeroplane, the combination with a sustaining plane, aerofoils carried thereby, vertical and horizontal rudders mounted back of the sustaining plane, and a body, said rudders being mounted to swing upwardly and downwardly relative to the sustaining plane, of a wheel mounted for rotation, connections between the wheel and the vertical rudder, a post upstanding from the wheel, a flexible connection between the post and wheel for transmitting rotary motion from said post to the wheel, yielding means for binding the post upon the wheel, oppositely extending connections between the post and the aerofoils, a rearwardly extending connection between the post and the horizontal rudder, a hand wheel mounted

for rotation upon the post, and means actuated by the hand wheel for shifting the rudders bodily upwardly or downwardly relative to the sustaining plane.

5 12. In a machine of the class described, a controlling element including a wheel, a post mounted thereon, a spring housed within the post, a fixed structure extending under the wheel, a flexible connection between the 10 spring and structure for binding the post yieldingly upon the wheel, a flexible power

transmitting connection between the post and wheel, and a hand wheel mounted for rotation on the post.

In testimony that I claim the foregoing as 15 my own, I have hereto affixed my signature in the presence of two witnesses.

EDWARD JACOB ELSAS.
